UNITED STATES PATENT OFFICE.

JOHN A. STAPLES, OF NEWBURGH, NEW YORK, ASSIGNOR TO STAPLES & HANFORD COMPANY, OF NEWBURGH, NEW YORK, A CORPORATION OF NEW JERSEY.

SPRINGWORK.

No. 813,924.

Specification of Letters Patent.

Patented Feb. 27, 1906.

Application filed April 26, 1904. Serial No. 205,035.

To all whom it may concern:

Be it known that I, JOHN A. STAPLES, a citizen of the United States, residing at Newburgh, in the county of Orange and State of New York, have invented certain new and useful Improvements in Springwork, of which the following is a specification.

This invention relates to wire structures, and particularly to means for connecting the ends of a connecting-wire to the opposite portions of a frame or other associated device.

In order to illustrate an application of my invention, I show and describe it in the present case in connection with springwork for beds, couches, and like articles of furniture.

In the accompanying drawings, which form a part of this specification, and which illustrate one exemplification of the invention, Figure 1 is a top plan view of a section of springwork constructed in accordance with my invention, the parts being broken away for convenience of illustration. Fig. 2 is a section on the line 2 2 of Fig. 1 looking in the direction of the arrow. Fig. 3 is a detail perspective view of a drop-wire spring-support, illustrating my invention and being broken away at its center for the convenience of illustration. Fig. 4 is a detail perspective view of a straight-wire spring-support, also showing my invention. Fig. 5 is a top view of a section of a frame and of one end of a wire-support having my attaching means and showing in dotted lines the support in its initial position for assembling the same on the frame and in full lines the position assumed by the support with relation to the frame when assembled in its normal position. Fig. 6 is a sectional view on the line 6 6 of Fig. 5 looking in the direction of the arrow and showing the support in place. Fig. 7 is a view showing the method of assembling the support on the frame.

In the drawings, the reference-letter A indicates the frame of a suitable spring structure—such, for example, as a bed-bottom or couch-top, composed of suitable side pieces *a* and end pieces *a'*. The sides and ends of the frame are composed of suitable rails, which may be of any suitable form. For example, they may be flat, as indicated in Fig. 6, or hollow and square in cross-section, as shown in Fig. 2, the corners of the frame being united in any suitable manner and the

shape or form of the frame being varied as occasion may require.

The springs *S*, only the lower ends of which are illustrated in the drawings for convenience of illustration, may be of any suitable type and are arranged and disposed on the frame in as many rows or ranges properly spaced apart as may be necessary and desirable for the structure being made. The lower ends of the springs *S* are mounted on or carried by suitable supports, to be hereinafter described, and the upper ends may be connected together to form a compact and properly-braced upper surface by any suitable connecting or bracing means usually employed in structures of this character.

The supports or connecting-wires *b* are provided at each end with a hook *b'* and a lateral wing or finger *b''*, which latter extend in opposite directions from the wires or supports at the opposite ends thereof. The frame is provided with opposite holes or openings so disposed as to correspond with the location and disposition of the rows or ranges of springs and forming seats for the ends of the wires. The holes in the frame are arranged in pairs, each two opposite holes forming a pair of seats for the ends of each supporting-wire. To assemble these supports, the support is rotated, as shown in dotted lines in Fig. 5, to bring the wing in substantially a vertical position over the hole, and the wing at this end of the wire is then introduced into the hole. The support is then turned to the position of full lines in Fig. 5, so as to move such wing up into engagement with the under face of the frame, as shown in Fig. 6, this wing then occupying a horizontal position. The wing at the opposite end of the support is then twisted or rotated in the direction of the arrow, Fig. 7, and as the opposite attached end abuts against the rail the support is thereby put under tension or torsion, and the free end having been rotated into a substantially vertical position, as shown in Fig. 7, it is then introduced into its associated hole in the frame, and as soon as it is released it springs up into engagement with the under face of the rail, this action being due to the torsion of the wire. The holes or openings to receive the ends of the wire being just large enough to permit of the passage of the wings and as the wings extend in the op

posite directions from the support, the support is held securely in interlocked relation with the rails. Inasmuch as it is necessary to put the wire-support under torsion in order to detach the supports from the rails, any risk of the supports becoming accidentally detached is overcome.

It is obvious that the wings may be at any angle; but I prefer to arrange them at right angles to the end portions, as thus they come flush up against the under face of the rail and are more rigidly held. The lengths of the hooks in practice will be approximately the thickness of the frame.

15 The particular form of the rail is immaterial, it being understood that any form of rail having an opening through which the wing may be passed and a surface or ledge against which the wings abut and against which it reacts when the support is in position may be employed.

In the form of structure shown in the drawings the connecting-wires constitute supports for the springs, and for this purpose I may employ either the drop-wire of Fig. 3 or the straight wire of Fig. 4. In the former the drop b^3 is provided at each end in a manner now well known in the art, and in either form they may be corrugated or bent throughout their lengths, or they may have eyes or bends at suitable intervals to form seats for the springs. The springs may be supported directly upon the supports in the seats provided by the bends or corrugations, or they may rest directly upon supplemental cross-wires b^4 , which in turn rest upon and are supported by the wires b , or the springs may rest directly upon both sets of wires at their points of crossing and may bind the wires together, as by interweaving therewith in a manner now well understood in the art. Any arrangement and organization of this part of the structure is within the scope of my invention, and in the preferred form, as illustrated in Fig. 2, the springs are rotated upon and interwoven with the two sets of wires at their several points of crossing. In this form the crossing wires b and b^4 have their ends attached to the side rails in the manner above described. The end portions of the wires resting upon the side rails may be provided with sets or rests b^5 for the springs of the edge rows S' where they rest upon the upper surface of the frame, whereby the spring edge is produced, as the springs S' when seated thereon will stand over the upper surface of the frame and their top coils will project flush with or beyond the outer edges of the rails. The springs of the edge rows are shorter than the springs of the interior rows in order to bring the tops of the same flush with or at substantially the same elevation as the tops of the interior springs.

By means of the interlocking connection between the side rails and spring-supports a

knockdown structure is provided which may be made by the manufacturer and may be readily and easily assembled at the factory or by the jobbers to be shipped ready for use. The interlocking connections described dispense with the employment of the auxiliary and independent means for attaching the supports to the frame, and the materials, including the spring-supports constructed as described, may be furnished by the manufacturer in knockdown form, so as to be compactly packed for shipment, and the connections between the parts are so easily and readily made that they may be assembled by unskilled laborers.

While I have shown my invention applied to springwork for furniture, it is obvious that it may be used in other branches of industry where wires or rods are associated with a frame—as, for example, in making screens, mats, grilles, and other structures.

What I claim, and desire to secure by Letters Patent, is—

1. In combination, a frame having opposite seats, and a rod provided with means at its ends interlocked with the seats and held against disengagement by the torsional resistance of the rod.

2. In combination, a frame having opposite seats, and a rod having its ends entering the seats and provided with wings held from disengagement with the frame by the torsional resistance of the rod.

3. In combination, a frame having opposite seats, a rod having its ends entering the seats and one of which ends is provided with a wing engaging the frame and held against displacement by the torsional resistance of the rod.

4. In combination, a frame having opposite seats, and a rod provided at its ends with vertical hooks adapted to the seats, and wings extending oppositely therefrom.

5. In combination, a pair of rails having opposite seats, and a rod provided at its ends with depending hooks entering the seats and oppositely-extending wings abutting against the rails.

6. In combination, a pair of rails having opposite openings, and a rod provided at its ends with oppositely-extending wings adapted to be sprung into the openings.

7. In combination, a pair of rails having opposite seats, a rod having hooks at the ends adapted to the seats, and oppositely and laterally extending wings engaging the rails and held against displacement by the torsional resistance of the rod.

8. In combination, a pair of rails having opposite seats, and a spring-support having angular ends entering the seats and one of which ends is sprung into its associated seat by putting the rod under torsion.

9. In combination, a pair of rails having opposite seats and a rod having lateral wings

passing through the seats and one of which wings is entered into its associated seat by rotation of the same against the torsion of the rod.

5 10. In springwork, the combination with a frame having side rails provided with oppositely-arranged holes, crossing spring-supporting wires having their ends bent to provide oppositely-extending wings adapted to 10 said holes and extending laterally therefrom in engagement with the rails, and springs interweaving with the said wires at their crossings.

11. In springwork, the combination with 15 a frame composed of rails provided with oppositely-arranged holes, spring-supports composed of crossing wires adapted to said holes and having lateral wings to pass within the holes and out of register therewith and

which are held against displacement by the 20 torsional resistance of the supports, and springs connecting said wires at their crossings.

12. In springwork, the combination with a frame composed of rails provided with oppositely-arranged holes, spring-supports composed of corrugated crossing wires, the ends of said wires having hooks adapted to rest in 25 said holes and oppositely-extending lateral wings adapted to engage the rails and prevent displacement thereof, and springs interwoven with said wires at their crossings.

In testimony whereof I affix my signature in presence of two witnesses.

JOHN A. STAPLES.
